HOWARD M. BARBER, OF PAWCATUCK, CONNECTICUT, ASSIGNOR TO C. B. COTTRELL & CO. SONS COMPANY, OF WESTERLY, RHODE ISLAND, A CORPORATION OF DELAWARE

WEB PERFECTING ROTARY PRINTING PRESS

Application filed July 1, 1931. Serial No. 548,138.

The object of my invention is to provide non-printing means in a web perfecting rotary printing press, for exerting a uniform blotting pressure on the non-perfected web throughout its printed portion, whereby the appearance of the printed portion on the first printed side of the web will be improved by the elimination of the variation in tone so prevalent where the printed matter on the first printed side of the web does not coincide with the printed matter on the second printed or perfected side of the web. This is particularly advantageous where pictures are printed on both sides of the web and the picture or pictures on the first printed side of the web do not coincide with the picture or pictures on the perfected side of the web.

In web perfecting rotary printing presses and especially in multicolor presses when the web is perfected immediately after its first side has been printed, the portion of the impression or printed matter on the first printed side of the web which coincides with the impression or printed matter on the second printed side of the web is subjected to blotting pressure by the form cylinders of the second printing unit which causes the said portion to offset to a greater extent and thus present a lighter and duller tone than where no pressure has been applied. This non-uniform pressure produces different shades in the impression on the first printed side of the web and the uniformity of the impression is therefore destroyed.

This variation in tone in the impression on the first printed side of the web is caused by the offset web on the impression cylinder of the second printing unit taking off more ink from the first printed side of the web where pressure is applied thereto by the form cylinders of the second printing unit.

To eliminate this variation in tone on the first printed side of the web due to this offsetting and to ensure a uniform tone and color in the impression on the first printed side of the web, I have provided an auxiliary pressure means which coacts in the present instance with the impression cylinder of the second printing unit before the web passes to the form cylinders of that unit for perfect-

ing the web, said auxiliary pressure means being utilized to apply pressure to the non-perfected web throughout its printed area or any desired part thereof so that the impression on the first printed side of the web will receive a uniform blotting pressure against the offset web, either entirely by the said auxiliary pressure means or by a combination of pressures by said auxiliary means and the form cylinders of the second printing unit.

A practical embodiment of my invention is represented in the accompanying drawing in which:

Fig. 1 represents a diagrammatic side view of so much of a double four color web perfecting rotary printing press as will give a clear understanding of my invention;

Fig. 2 represents a detail face view of the perfected side of a web, illustrating a condition where the impression on the first printed side of the web does not coincide with the impression on the second printed side of the web, as commonly occurs;

Fig. 3 represents a detail face view of a pressure roller which, in this instance, has its surface built up to exert pressure on the non-perfected web at this point which will not receive pressure from the form cylinders of the second printing unit in perfecting the web.

The first multicolor printing unit may comprise an impression cylinder 1 and four form cylinders 2, 3, 4, 5, coacting therewith to print the first side of the web 6 in four colors.

The second multicolor printing unit may comprise an impression cylinder 7 and four form cylinders 8, 9, 10, 11 coacting therewith, to perfect the web by printing in four colors on its opposite side.

The offset web is denoted by 12 and it is passed in the usual manner around the impression cylinder 7 of the second printing unit.

The means which I have shown for exerting blotting pressure upon the desired portion or portions of the non-perfected web against the offset web 12 before the web is perfected by the form cylinders 8, 9, 10, 11, comprises a cylinder 13 mounted in position

to engage the non-perfected web as it passes around the impression cylinder 7 of the second printing unit over the offset web 12 and before the non-perfected web is engaged by 5 the form cylinders of the second printing unit.

This pressure cylinder 13 is used to exert pressure upon the entire non-perfected web or upon any desired portion thereof by building 10 up the face of the cylinder with any suitable material as metal, paper, etc. In the present instance the face of the pressure cylinder 13 is built up as shown at 14, to exert blotting pressure upon the non-perfected web 15 at those points which will not receive pressure from the form rollers 8, 9, 10, 11 when perfecting the web.

The form cylinders 2, 3, 4, 5 of the first printing unit may be positively driven from 20 the impression cylinder gear 15 through the gears 16, 17, 18 and 19 respectively. The form cylinders 8, 9, 10, 11 of the second printing unit may be positively driven from the impression cylinder gear 20 through the 25 gears 21, 22, 23 and 24 respectively. The blotting pressure cylinder 13 may also be positively driven from the impression cylinder gear 20 through the gear 25. The impression cylinder gears 15 and 20 of the two 30 printing units may be driven in unison through the gears 26, 27, bevel gears 28, 29, shaft 30, bevel gears 31, 32 and gears 33, 34.

From the above description it will be seen 35 that I have provided non-printing means whereby the impression on the first printed side of the web may be subjected to blotting pressure in whole or in part, as the case may be, to obtain a uniform tone and color which is so much to be desired in web perfecting 40 work.

While I have described my invention in connection with a double multicolor web perfecting press I do not wish to limit myself to such a press but contemplate the use of this 45 auxiliary pressure means in connection with presses which perfect in one or more colors.

It is evident that various changes may be resorted to in the construction, form and arrangement of the several parts without departing from the spirit and scope of my invention, and hence I do not intend to be limited 50 to the particular embodiment herein shown and described, but

What I claim is:—

- 55 1. In a web perfecting rotary printing press, first and second printing units, and non-printing means coacting with the second printing unit for exerting blotting pressure on more or less of the non-perfected web.
- 60 2. In a web perfecting rotary printing press, first and second printing units, an offset web passing around the impression cylinder of the second printing unit, and non-printing means coacting with said offset

web on the impression cylinder for exerting blotting pressure on more or less of the non-perfected web.

3. In a web perfecting rotary printing press, first and second printing units, and a 70 non-printing pressure cylinder coacting with the impression cylinder of the second printing unit for exerting blotting pressure on more or less of the non-perfected web.

4. In a web perfecting rotary printing 75 press, first and second printing units, an offset web passing around the impression cylinder of the second printing unit, and a non-printing pressure cylinder coacting with the offset web on the second impression cylinder 80 for exerting blotting pressure on more or less of the non-perfected web.

5. In a web perfecting rotary printing press, first and second printing units, and a non-printing pressure cylinder having its 85 face built up at predetermined points for coaction with the impression cylinder of the second printing unit to exert blotting pressure on predetermined portions of the non-perfected web.

6. In a web perfecting rotary printing press, first and second printing units, an offset web passing around the impression cylinder of the second printing unit, and a non-printing pressure cylinder built up at pre- 95 determined points to exert blotting pressure on the non-perfected web at those portions of its impression which will not be subjected to pressure by the form cylinder or cylinders of the second printing unit.

In testimony, that I claim the foregoing as my invention, I have signed my name this 29th day of June, 1931.

HOWARD M. BARBER.
